UNITED STATES PATENT OFFICE.

HERMANN BUEHL, OF PHILADELPHIA, PENNSYLVANIA.

DESIGN FOR A BOX.

SPECIFICATION forming part of Design No. 23,947, dated January 8, 1895.

Application filed August 20, 1894. Serial No. 520,849. Term of patent 3½ years.

To all whom it may concern:

Be it known that I, HERMANN BUEHL, a citizen of the United States, residing in the city and county of Philadelphia, State of Pennsylvania, have invented and produced a new and original Design for Candy and other Boxes, of which the following is a specification, reference being had to the accompanying drawing, forming part thereof.

5 The leading feature of my design for a candy and other box, is the body of the same simulating a rocking cradle and the figure of a child thereon.

In the drawing: A designates the body of the box, the bottom B of the same being rounded, 15 thus simulating a rocking cradle.

C designates the lid having thereon the figure of a child.

What I claim is—

10 The design for a candy box substantially as described and shown.

HERMANN BUEHL.
